CLAIM

The ornamental design for a onesie, as shown and described.

DESCRIPTION

FIG. 1 is a diagram illustrating a perspective front view of an example onesie.

FIG. 2 is a diagram illustrating a perspective back view of the example onesie of FIG. 1, further illustrating the onesie.

FIG. 3 is a diagram illustrating a front elevation view of the example onesie of FIG. 1, further illustrating the onesie.

FIG. 4 is a diagram illustrating a rear elevation view of the example onesie of FIG. 1, further illustrating the onesie.

FIG. 5 is a diagram illustrating a left-side elevation view of the example onesie of FIG. 1, further illustrating the onesie.

FIG. 6 is a diagram illustrating a right-side elevation view of the example onesie of FIG. 1, further illustrating the onesie.

FIG. 7 is a diagram illustrating a top plan view of the example onesie of FIG. 1 in an unsnapped configuration and further illustrating the onesie.

FIG. 8 is a diagram illustrating bottom plan view of the example onesie of FIG. 1 in an unsnapped configuration and further illustrating the onesie.

FIG. 9 is a close-up view thereof, as referenced in FIG. 2. FIG. 10 is a diagram illustrating a perspective view of the example onesie of FIG. 1 as a baby may wear the onesie; and,

FIG. 11 is a diagram illustrating a perspective view of the example onesie of FIG. 1 as a baby may wear the onesie, the onesie in an unsnapped configuration.

The broken lines in the drawings represent stitching on the onesie that form no part of the claimed design.

The broken lines in FIG. 2 represent the boundaries of the enlarged view shown in FIG. 9.

The wavy broken line in FIG. 9 indicates a boundary and forms no part of the claimed design.

The partial human figure shown in broken lines is environmental subject matter included to illustrate how the design may appear when worn and forms no part of the claimed design.

1 Claim, 9 Drawing Sheets
